UNITED STATES PATENT OFFICE.

EDWARD W. BURGESS, OF MILWAUKEE, WISCONSIN, ASSIGNOR TO A. O. SMITH CORPORATION, OF MILWAUKEE, WISCONSIN, A CORPORATION OF NEW YORK.

DESIGN FOR A STEEL GRID FOR FLOORS AND PAVEMENTS.

Application filed June 6, 1928. Serial No. 27,013. Term of patent 14 years.

To all whom it may concern:

Be it known that I, EDWARD W. BURGESS, a citizen of the United States, residing at Milwaukee, in the county of Milwaukee and State of Wisconsin, have invented a new, original, and ornamental Design for Steel Grids for Floors and Pavements, of which the following is a specification, reference being had to the accompanying drawing, forming part thereof.

The figure is a perspective view of a steel grid for floors and pavements, showing my new design.

I claim:

The ornamental design for a steel grid for floors and pavements, as shown.

EDWARD W. BURGESS.
